CLAIM

The ornamental design for a garment hanger, as shown and described.

DESCRIPTION

FIG. 1 is a top and front perspective view of a garment hanger showing our new design according to a first embodiment;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a cross-sectional view taken along the line 8-8 of FIG. 1;

FIG. 9 is a top and front perspective view of a garment hanger showing our new design according to a second embodiment;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom plan view thereof; and,

FIG. 16 is a cross-sectional view taken along the line 16-16 of FIG. 9.
